UNITED STATES PATENT OFFICE.

ROY W. SEXTON, OF WYTHEVILLE, VIRGINIA.

FLAT PACKAGE.

1,229,799.

Specification of Letters Patent. Patented June 12, 1917.

Application filed January 11, 1917. Serial No. 141,749.

To all whom it may concern:

Be it known that I, ROY W. SEXTON, a citizen of the United States, and a resident of Wytheville, county of Wythe, and State 5 of Virginia, have invented certain new and useful Improvements in Flat Packages, set forth in the following specification.

This invention relates to the packaging and dispensing of such articles as embroidery forms. An embroidery form is an article intended to serve both as a pattern and as a filler for embroidery threads applied by hand to a textile fabric such as an article 10 of table linen. The embroidery forms are more or less fragile and subject to injury by handling before they are actually fixed in position to a piece of linen which is to be embroidered. It is an advantage in the selling of such articles that they be displayed in such a manner that the prospective 15 purchaser can see the actual design and also the general nature of the structure of the form but, at the same time, it is necessary to protect the form from injurious handling 20 and from the injurious action of the atmosphere.

In view of the fact that embroidery forms commonly embrace all the letters of the alphabet, each in many sizes and each in many 25 styles of type, it is advantageous to provide for packaging in such a way that a classified arrangement may be maintained. It is likewise desirable to accomplish the packaging in such a manner as to take up as little space 30 as possible, while maintaining the other enumerated advantages.

The object of the present invention is to provide an embodiment to achieve the afore- 35 enumerated desirable features both singly 40 in sub-combination and in complete combination.

The invention will better be understood by reference to the illustrative embodiments to which the claims are directed and which 45 are described in the following specification in connection with the drawings, which form a part hereof. In the drawings Figure 1 is a front elevation of the envelop for the unit package; Fig. 2 is a front elevation 50 illustrative of an article of the type to be dispensed; Fig. 3 is a front elevation of a label for use with the envelop of Fig. 1; Fig. 4 is a front elevation of a complete unit package; Fig. 5 is a vertical section 55 through the structure of Fig. 4; Fig. 6 is a front elevation, with parts broken away,

showing a flat package; and Fig. 7 is a perspective view showing a filing cabinet containing a number of multiple unit packages. 60

A backing 1, in the form of a flat, opaque label, is provided and is selected so that its outer surface 2 is of a frictional character. The label 1 may conveniently be provided with nomenclature along the top margin 65 such as the symbols 3 and 4, to identify the classification of the article in the package. It is not, however, necessary to provide the label 1 with a reproduction of the design of the article such as the embroidery 70 form 5, representing the letter D, as shown in Fig. 2, as will presently appear. The advantage of this is apparent in that one set of labels with the designation as indicated by 3 and 4 is sufficient for an entire 75 alphabet of the size and pattern, one letter of which is indicated by the D of Fig. 2. This reduces the number of separate kinds of labels twenty-six times for the letters of the alphabet alone. In any suitable manner 80 the three elements, the label 1, the embroidery form 5, and the envelop 6, are brought into assembled relation, as indicated in Fig. 4. The embroidery form 5 may be placed with its rear face, which usually 85 has somewhat sharp edges, and readily grips any frictional surface, upon the frictional surface 2 of the label 1 so that its outer, somewhat convex, surface is exposed. The envelop 6 may then be folded and fab- 90 ricated about the label 1 and the form 5 or the two parts 1 and 5 may be inserted into the previously fabricated envelop 6 and the same sealed up. The actual manner of as- 95 sembling these parts is more or less depend- 100 ent upon whether hand work or automatic machinery is employed. Whichever the method of assembling, it should be such that the positioning of the article such as 5 on the face 2 of the label 1 and inside the envelop is haphazard, it being understood 105 that the label and envelop are preferably considerably larger than the article such as the embroidery form 5. This haphazard assembling sometimes positions the em- 110 broidery form 5 centrally, as shown in Fig. 4, and sometimes more or less to one side and toward the bottom or top of the inclosure. In other words, this haphazard positioning of the embroidery form is in- tentional but, when once assembled as shown in Fig. 4, the outer face 8 of the envelop 6

5 presses the embroidery form 5 against the frictional surface 2 of the label 1 and its relative position remains stationary. The envelop 6 should be such that its outer face 8 is transparent. This is readily accomplished by fabricating the envelop out of what is known as "glacine" paper. This transparent quality displays not only the pattern of the embroidery form, but its texture and its thickness may both be determined quite easily by the sense of touch from the entire package.

10 A retail store must keep on hand, of course, more than one of each particular embroidery form and they must be kept in such a way as to be readily accessible at the call of a customer. To this end a number, say a dozen or more of the individual packages shown in Fig. 4 are assembled by 15 superposing one on the other, and are inclosed in a filing envelop 10, which bears legends 30 and 40, corresponding to the individual package legends 3 and 4, and, in addition, a designation 11 corresponding to 20 the pattern of the embroidery form. Great economy in the total thickness of an assembled flat package such as that shown in Fig. 6, is brought about by the haphazard arrangement of the individual embroidery 25 forms 5 contained. If the embroidery forms were all similarly positioned, the package would, of course, take on the summation of the thicknesses of the total number of forms. The haphazard arrangement reduces this total thickness.

30 Any suitable number of the flat packages 10 may be assembled in a dispensing cabinet 12, it being possible to arrange the flat packages alphabetically, as indicated in Fig. 1. 40 It is preferred that each of the envelops making up the multiple unit package have a section 13 along the upper end, which is weakened by a series of perforations 14, so that it may readily be torn off. When this 45 end portion is torn off the outer containing envelops are just as easily maintained in an indexed arrangement, and the contents of each envelop are accessible for the dispensing of one or more of the individual package embroidery forms. In some instances a 50 retail dispenser may prefer to open each of

the outer envelops 10 immediately upon receiving his stock from the manufacturer or, if desired, the outer envelops may be kept closed until an actual call by a customer has 55 been made for an embroidery form contained therein.

What is claimed and what is desired to be secured by United States Letters Patent is:

1. A dispensing package for embroidery 60 forms comprising, a flat opaque label having a friction surface; a single embroidery form of a size smaller than said label lying face up in frictional contact upon said friction surface and otherwise free to move 65 across said label; and an envelop of transparent air-excluding material completely inclosing both said label and said embroidery form and maintaining said frictional contact for all positions of the three part unit 70 comprising the label, the embroidery form and the envelop but aiding a haphazard positioning of said embroidery form upon said label.

2. A dispensing package for embroidery 75 forms comprising a flat label having a friction surface; a single embroidery form of a size smaller than said label lying face up in frictional contact upon said friction surface, and otherwise free to move across said 80 label; an envelop of transparent air-excluding material completely inclosing said embroidery form and the friction surface of said label and tending to maintain said frictional contact for all positions of the three- 85 part unit comprising the label, the embroidery form and the envelop but aiding an initial haphazard positioning of said embroidery form upon said label; a plurality of said three-part units superposed one on 90 another and forming a stack of substantially uniform thickness because of the haphazard distribution of the embroidery forms; and a pocket for holding said stack in assembled relation and exerting pressure 95 upon said stack to increase said frictional contact between the embroidery form and label of each said three-part unit.

In witness whereof I have signed my name to this specification, this 3rd day of 100 January, 1917.

ROY W. SEXTON.
